US0D1105606S

(12) **United States Design Patent** (10) **Patent No.:** **US D1,105,606 S**
(45) **Date of Patent:** **** Dec. 9, 2025**

(54) **SAFETY RAZOR**

(71) Applicant: **KAI R&D CENTER CO., LTD.**, Seki (JP)

(72) Inventor: **Hiroshi Yamakose**, Seki (JP)

(73) Assignee: **KAI R&D CENTER CO., LTD.**, Seki (JP)

(**) Term: **15 Years**

(21) Appl. No.: **29/960,099**

(22) Filed: **Aug. 29, 2024**

(30) **Foreign Application Priority Data**

Mar. 8, 2024 (JP) ..... 2024-004836 D
